UNITED STATES PATENT OFFICE

2,571,914

RAILROAD TIE REMOVER

Emil W. Maves, Stanley, Wis., assignor of one-half to A. R. Heagle, Stanley, Wis.

Application August 13, 1947, Serial No. 768,433

1 Claim. (Cl. 254—43)

1
This invention relates to a railroad tie remover. It is an object of the present invention to provide a tie remover which is adapted to be carried upon a wheel truck that may traverse the rails and will support the remover in a manner by which it is easily accessible for engagement with the end of a tie and whereby the same can be swung to an out-of-use position for the purpose of transport.

Other objects of the present invention are to provide a tie remover which is of simple construction, inexpensive to manufacture, convenient to use and efficient in operation.

For other objects and for a better understanding of the invention, reference may be had to the following detailed description taken in connection with the accompanying drawing, in which

Fig. 1 is a side elevational view of the tie remover embodying the features of the present invention and a section being taken through the supporting rod which connects the tie remover with the truck.

Fig. 2 is a top plan view of the tie remover.

Fig. 3 is a longitudinal cross-sectional view of the tie remover taken on line 3—3 of Fig. 2 and with the operating arm extended rearwardly and before its advancement to push the tie.

Fig. 4 is a cross-sectional view taken generally on the same line 3—3 of Fig. 2 but with the operating handle pivoted forwardly to again position the dog for effecting the advancement of the railroad tie upon the return stroke of the operating arm.

Fig. 5 is a fragmentary end elevational view of the tie remover.

Fig. 6 is a top plan view of the tie remover and the supporting connections for the same on the truck and illustrating with dotted lines how the tie remover can be pivoted upon its support from the truck and rested upon a bracket for the purpose of being transported by the truck.

Figure 7 is a section through the bar mounting carrier, taken on line 7—7 of Figure 4.

Referring now to the figures, 10 represents a railroad tie which is mounted beneath rails 11 and 12. Adapted to traverse the rails is a truck 13 having wheels 14 resting on the rails. Extending from one corner of the truck is a long heavy supporting arm or bracket 15 pivoted by a bolt 16 to the truck and pivotally connected at its outer end and as indicated at 17 to pivotally support a main body or carrier 18 to which the various parts of the tie remover as indicated generally at 19 are operatively connected. This body 18 has a flat bottom plate or base 21 and

2
upright portions or side plates 22. The body is connected to the supporting arm 15 by its upright portion 22 at the one side of the body. Between the side or upright portions 22 there are extended guide rollers 23 and 24 on which an adjustable pusher member or rack bar 25 is rested. The adjustable member has a pointed end 26 which engages with the end of the tie 10 to push the same from beneath the rails 11 and 12. On the rear end of the adjustable member 25 is a handle 26 which may be grasped to withdraw the member 25 from its engagement with the tie 10. On a medial portion of the top of the member 25 are ratchet teeth 27 adapted to be engaged by a pawl 28 of an operating member 29 pivoted as indicated at 30 between the upright portions 22. A flanged roller 22' straddles the ratchet teeth 27 and engages the member 25 at the sides of the teeth 27 to maintain the member 25 on the rollers 23, 24. The socket member 29 has an opening therein for receiving a long operating handle or hand lever 31. When the handle is not in place, a projection 33 with a ball handle 34 thereon can be used to reciprocate the member 29 on the pivot 30.

The member 29 is pivoted between the portions 22 as indicated at 35 and on the same pivot there extends a handle 36 by which the tie remover can be lifted. Also on the pivot 35 is a forwardly extending arm 37 which has downwardly extending projections 38 thereon for engagement with the rails. As the member 29 is pivoted in a clockwise direction as viewed on the figures, the pawl 28, when in engagement with the teeth 27, will advance the member 25 and the tie 10 so as to push the tie from beneath the rails 11 and 12.

Pivoted to the pawl 28 is a handle 41 which can be used for lifting the pawl to release the bar 25. As the handle and the member 29 are adjusted from the positions shown in Figs. 1 and 3 to the position shown in Fig. 4, the member 25 and the tie 10 will be advanced continually as the operating member 29 is worked back and forth and until the full length of the adjustable member 25 has been extended beyond the main body 18.

When it is desired to transport the device, the bolt 16 may be removed and the device bodily carried on truck 13 or else the arm 37 and the adjustable member 25 with the main body 18 can be pivoted on pivot 17 in a clockwise (Fig. 6) direction so that the adjustable member 25 can be pulled back and rested on a laterally supporting arm 45 on the truck 13 in which case por-

tions of the device overhang the ties and do not interfere with movement of truck 13.

To return the adjustable member 25, the pawl 28 is raised and by means of the handle 26 the adjustable member 25 can be withdrawn through the body 18 and upon the rollers 23 and 24.

While various changes may be made in the detail construction, it shall be understood that such changes shall be within the spirit and scope of the present invention as defined by the appended claim.

I claim:

In a railroad tie remover, the combination which comprises a rack bar having ratchet teeth in the upper edge adapted to be positioned against one end of a railroad tie and suspended whereby it is aligned with the tie, a carrier comprising a base having upwardly extended side plates positioned around the rack bar and having guide rollers positioned above and below the said rack bar; a socket member positioned in the upper part of the carrier, a pin pivotally mounting the said socket member in the side plates of the carrier with the said socket member positioned above the rack bar, a pawl pivotally mounted on the lower end of the said socket member at a point spaced below the pin pivotally mounting the

socket member in the side plates of the carrier, said pawl positioned to engage the said ratchet teeth of the rack bar, a forwardly extended arm having downwardly extended projections thereon positioned to engage a rail on the said tie pivotally connected to the said socket member by the pin mounting the said socket member in the side plates of the carrier, and a handle extended from the said socket member.

EMIL W. MAVES.
